DESIGN FOR A MOCCASIN OR SIMILAR ARTICLE

Edward J. Biel, Brookline, Mass.

Application December 17, 1937, Serial No. 73,689

Term of patent 3½ years

To all whom it may concern:

Be it known that I, Edward J. Biel, a citizen of the United States of America and resident of the city of Brookline, county of Norfolk, State of Massachusetts, have invented a new, original, and ornamental Design for a Moccasin or Similar Article of which the following is a specification, reference being had to the accompanying drawing, forming a part thereof.

In the drawing,

Figure 1 is a top plan view of a moccasin or similar article, showing my new design; Fig. 2 is a side elevational view thereof; and Fig. 3 is a rear elevation thereof.

I claim:

The ornamental design for a moccasin or similar article, substantially as shown.

EDWARD J. BIEL.
